(57) CLAIM

The ornamental design for a cookware handle, as shown and described.

DESCRIPTION

FIG. 1 is a top, front, left perspective view of a cookware handle showing our new design therefor;

FIG. 2 is a right side elevational view thereof;

FIG. 3 is a left side elevational view thereof;

FIG. 4 is a front elevational view thereof;

FIG. 5 is a top plan view thereof; and,

FIG. 6 is a bottom plan view thereof.

Throughout the drawing, broken lines show environment and form no part of the claimed design.

1 Claim, 6 Drawing Sheets
